UNITED STATES PATENT OFFICE

HENRY C. MAUL, OF DETROIT, MICHIGAN, ASSIGNOR TO DETROIT MICHIGAN STOVE COMPANY, OF DETROIT, MICHIGAN, A CORPORATION OF MICHIGAN

DESIGN FOR A COMBINED HEATER CASING AND FIRE BOX

Application filed June 16, 1930. Serial No. 36,051. Term of patent 7 years.

To all whom it may concern:

Be it known that I, HENRY C. MAUL, a citizen of the United States, residing at Detroit, in the county of Wayne and State of Michigan, have invented a new, original, and ornamental Design for Combined Heater Casing and Fire Box, of which the following is a specification, reference being had to the ac-

companying drawing, forming part thereof.

The figure is a perspective view of the article, showing my new design.

I claim:—

The ornamental design for a combined heater casing and fire box substantially as shown.

HENRY C. MAUL.
